5 Claims. (Cl. 96—45)

This application is a continuation-in-part of Application Serial No. 12,541 filed March 3, 1960, now abandoned.

The present invention relates to a contact screen for use in making a printing block from a picture having areas of optical density, and to a printing member, such as a printing block, produced by using the contact screen.

The contact screen of the present invention is of the type of contact screen having groups of small, light-transmitting areas, each group being constituted by areas of different optical densities and of congruent shape, and each group having light-transmitting areas of all densities. The light-transmitting areas adjoin one another and adjoining areas of adjacent groups, and each group has sub-groups the areas of which have an identical optical density. The densities of said sub-groups are different from each other.

This type of contact screen is described in French Patent 336,056, and can be employed for the reproduction of a picture of an object to be depicted in the form of one or more series of dots, all dots of one series having the same color and the same degree of transmission or reflection, the total area of the dots of a series in a certain portion of the picture being a function of the relative brightness of the corresponding portion of the object. The printed dots of a series all have the same size, the number of dots in a given portion of the picture being such that this portion of the picture has the desired overall degree of reflection or transmission.

In the performance of such a method by means of this known contact screen, a number of difficulties are encountered.

Since this known contact screen is manufactured by superposing bands of material with certain optical densities in various patterns, the optical densities of the light-transmitting areas, as far as their mutual differences are concerned, are determined by the selection of the optical densities of the single bands used. A second limitation of this prior art contact screen is that the number of density levels which can be present in the screen is determined by the number, the mutual difference in shape and optical densities, and the possibilities regarding the geometrical arrangement, of the bands. The number of levels is also limited because the geometrical configuration cannot be extended at will. If, for example, more than three bands are used, a greater number of areas of higher densities is indeed obtained, but on the other hand more and more areas of lower densities are lost. A fourth restriction of the prior screen is in the number of areas of the same optical density within one group. In the prior art screen, this number is determined by the number, the optical value, and the location of the bands. A fifth limitation of the prior screen is in the interrelation of the location of the areas of different optical densities. As a matter of fact, this is entirely determined by the arrangement of the bands. The result of these five limitations on the freedom of using the prior contact screen is that the distribution of the optical densities in the screen plate cannot be adapted to the demands to be made in connection with a true representation of the differences in brightness of the object to be depicted. Hence it is, in particular, not pos-

2

sible to obtain an adaptation to the characteristics of the photographic and printing means employed. A further consequence of the relatively limited arrangement of the areas of different densities is that there is an increased chance of the printed dots in the printed picture adjoining each other.

It is an object of the present invention to provide a contact screen which does not have the limitations of the prior art screen.

10 It is an object of the present invention to provide a contact screen in which the densities of the steps, the number of steps, the number of areas per density value, and the relative positions of the areas may be selected so that any desired adaptation of the negative to be reproduced can be obtained.

To this end, the contact screen according to the invention is characterized in that number of sub-groups and their densities and the number of areas in each sub-group can be selected without any limitations imposed by the 20 fact that the screen is a configuration of intersecting bands.

An additional degree of freedom can be obtained, according to the invention, by varying the relative positions of the areas in the various groups. This enables a further 25 adaptation to the requirements of a specific reproduction to be depicted.

Since the optical densities can be freely selected as far as their value is concerned, it is of importance, and it is possible according to the present invention, so to select 30 the densities of the various areas such that the said densities constitute an arithmetical series, the logarithm of the relative number of areas of a given density being at least a substantially linear function of the said density.

It is of particular advantage for the light transmitting 35 areas to have the shape of a regular hexagon.

The invention also relates to a printing block made by means of a contact screen as described herein.

The invention will be illustrated hereinafter with reference to the accompanying drawings, in which:

40 FIG. 1 is a section, on enlarged scale, through a negative, a photographic positive material and a screen according to the invention;

FIG. 2 is a graph showing the relationship between the magnitudes of values which play a part in the method 45 and in the screen according to the invention;

FIG. 3 is a greatly enlarged plan view of a preferred shape of the small light transmitting areas of the screen according to the invention;

FIG. 4 is an illustration of one way in which the contact screen can be built up; and

FIG. 4A is an enlarged view of part GI of FIG. 4 showing the screen with the areas of different densities represented therein.

55 In the method of reproducing a negative using a screen according to the invention, the same steps can be used as those for conventional screening methods, the contact screen according to the invention being used in the same step as the well-known screens formed by engraved optical glass. However, the particular adjustments and auxiliary

60 treatments, which are necessary when using the well-known screens, are rendered superfluous by using the screen of the present invention. The invention, however, can be best understood by means of a specific example, the example here being the case where a transparent black and white negative picture is translated into dots (a screened picture) on a photo-sensitive material.

65 Hereinafter the transparent black and white negative will be called the "negative" for short and the picture thereof made on the photo-sensitive material will be called the 70 "positive."

In FIG. 1 the numeral 1 represents the negative and

2 the positive, both in section. The numeral 3 designates a contact screen according to the invention, the construction and the operation of which will be explained hereinafter. As appears from this figure, the negative comprises a number of areas of different transmissivity. The transmissivity can be expressed as $\tau = I/I_0$ (also called transmission factor or in the case of reflection the reflection factor), in which I_0 is the amount of incident light and I the amount of transmitted light. Inasmuch as the human eye sees as differences in luminous intensity what actually are ratios of luminous intensity, it is in many cases advisable to express the blackening of the photographic material by the density $D = \log 1/\tau = -\log \tau$; $D=0$ therefore corresponds with $\tau=1.0$ or 100%, $D=1$ corresponds with $\tau=0.1$ or 10%, $D=2$ corresponds with $\tau=0.01$ or 1% etc. The transmissivity ratios are converted into differences in density by the use of logarithms, which is in accordance with the impressions of the human eye.

In order to obtain a true reproduction of the negative 1 on the positive 2 in the case under consideration, the distribution of densities in the negative must be represented in the positive in a reverse sense, and according to the invention this must be effected by means of a pattern of dots, which consists of dots of equal size, the areas having differences in photographic density being reproduced in the positive by areas having differences in the relative number of dots.

The positive material 2 has a very high gamma-value, which means that when a certain exposure dose is reached and then exceeded, a heavy blackening is obtained substantially immediately, whereas below such threshold dose no blackening takes place. Furthermore it is assumed that the density range i.e. the differences between the greatest and the least density in the negative amounts to 2.00 and that during the printing the exposure dose will be such that for a negative density $D=2.00$ the threshold dose at which blackening of the positive material will take place is just not reached.

Seeing that the half-tone positive is afterwards converted into a printing means (e.g. a half-tone block or an offset plate) which is used for printing the ultimate picture, the positive 2 may be regarded here as if it were replaced by the printed image.

The object of the method of reproducing the negative is to have the positive and thus the printing means formed therefrom divided into dots in such a manner that the number of dots per unit of surface area determines the density of the relevant portion of the image. To achieve this end the relationship between the number of dots and the image density resulting therefrom is first established. Let us suppose that a black printing ink is used which has a density $D=1.50$, so a reflection or transmission factor $\tau_z=0.032$, while the paper has a reflection factor $\tau_w=1.00$ ($D=0.00$). If the relative area covered by printed dots, i.e. the number of printed dots actually in the area in question divided by the number of dots that could possibly be printed in the area, is equal to n , the remaining white area having no dots thereon has a size of $(1-n)$. The total reflection factor then is

$$\tau = nx0.032 + (1-n)1.00 = -0.68xn + 1.00$$

or

$$n = \frac{1-\tau}{0.968},$$

and in general

$$\tau = nx\tau_z + (1-n)x\tau_w, \text{ or } n = \frac{\tau_w - \tau}{\tau_w - \tau_z} \quad (1)$$

The number of dots for obtaining a certain value of τ is hence proportional to $1-\tau$, and is even substantially equal thereto.

According to the present invention, the contact screen 3 which is used comprises a large number of small areas

of equal size and of different transmissivity, which areas are arranged in mutually identical groups, each containing sub-groups of areas having the same densities, and the different sub-groups in a group of areas having different density such that each group has areas of all transmissivities that are employed. In a preferred embodiment according to the invention, the densities of the sub-groups of areas within a group form an arithmetical series; in the subjoined example it is assumed that the difference in density between the successive densities of the sub-groups amounts to 0.20, the extreme values being 0.00 and 2.00.

The negative as shown in FIG. 1 is likewise divided into zones between which there is a difference in density of 0.20, the lowest and highest densities being 0.00 and 2.00 respectively. It has already been stated that in the example under consideration the exposure dose given to the negative is such that the light transmitted by the zones of the negative where $D=2.00$ is not quite sufficient to effect blackening of the positive, so that even in combination with the fully transparent areas of the screen where $D=0.00$ and the light transmitted by the negative through the zones where $D=2.00$ is insufficient to produce a black spot in the positive. The zones of the negative where $D=1.80$ will transmit sufficient light to cause blackening of the positive behind the screen areas where $D=0.00$, but not sufficient to cause a blackening behind the areas of the screen where $D=0.20$ or greater. Accordingly, in the zones of the positive which correspond with the zones of the negative where $D=1.80$, a number of black dots will form which number is equal to the number of screen areas where $D=0.00$; the picture in these zones must have a density $D=0.20$ to have a difference in density from the preceding zones in which no dots are printed at all which is the same as the difference in density between the corresponding portions of the negative. The zones of the negative where $D=1.60$ will transmit sufficient light to produce a blackening behind the screen areas where $D=0.20$ as well as a blackening of the positive behind the screen areas where $D=0.00$. Accordingly, in the corresponding zones of the printed image, there is present a number of black dots that is equal to the sum of the number of screen areas where $D=0.00$ and $D=0.20$. Any subsequent zone of the negative of lower density will form a new group of dots in the positive, which dots contribute towards the blackening as is intended.

It is still necessary to determine how many screen areas of a certain transmissivity are required to effect the desired blackening in the screened positive. It follows from the foregoing that a zone of the positive having a certain blackening contains a number of dots which is equal to the number of dots in positive portions that are less black plus a number of additional dots, which latter number equals the number of areas of the screen of the greatest density that is still operative in this zone of the positive. The number of additional dots necessary to produce each successive density level can be determined, therefore, as the difference between the total number of dots of said level and the number of dots which produce the preceding level.

The relationship between the reflection factor of a portion of a printed image and the relative number of dots required therefore has already been established hereinbefore [Formula (1)]. Said number of dots, naturally, is equal to the number of black dots in the positive which was used for manufacturing the printing means. However, there is a difference between the extent of blackening of the positive and that of the printed image; for the printing ink used has, as was assumed, a density of 1.50, so that the maximum density and hence the degree of blackening achievable likewise amounts to 1.50. Because in the printed image the same number of density levels must be present as in the negative, the difference

in density between said levels in the printing means amounts to 0.15 instead of 0.20.

The subjacent table is a tabulation of the calculation outlined above; in this table $D_{i,\max}$ is the density of the screen areas that are just operative and n_i the additional number of said areas necessary for that density as compared to the area of the next preceding density level.

D_{neg}	D_{pos}	D_{print}	τ_{print}	$n = \frac{1-\tau}{0.908}$	$D_{i,\max.}$	n_i
2.00	0.00	0.00	1.000	0.000	---	---
1.80	0.20	0.15	0.708	0.302	0.00	0.302
1.60	0.40	0.30	0.501	0.516	0.20	0.214
1.40	0.60	0.45	0.355	0.666	0.40	0.150
1.20	0.80	0.60	0.251	0.774	0.60	0.108
1.00	1.00	0.75	0.178	0.849	0.80	0.075
0.80	1.20	0.90	0.126	0.903	1.00	0.054
0.60	1.40	1.05	0.089	0.941	1.20	0.038
0.40	1.60	1.20	0.063	0.968	1.40	0.027
0.20	1.80	1.35	0.045	0.987	1.60	0.019
0.00	2.00	1.50	0.032	1.000	1.80	0.013

FIG. 2 is a graph in which the uppermost curve, the dots-dash curve, shows the relationship between the relative number n of printed dots and the density provided thereby. The dashed-line curve shows the relationship between the relative number of n_i of additional dots and the printed density, and the full-line curve shows the relationship between n_i and the density of a given set of screen areas. The last-named curves turn out to be straight lines, the inclination of the latter being equal to -0.74 ; so that the following equation holds good:

$$\log n_i = -0.74x D_i - 0.525$$

or in general

$$\log n_i = -ax D_i - b \quad (2)$$

For a different number of subdivisions of the density of the screen areas or another density of the printing ink, the coefficients a and b can be calculated in a corresponding manner.

It has been indicated by means of arrows in the graph that the calculated values of n_i are equal to the corresponding densities of the print and the screen. The associated densities differ, it is true, but they can be simply deduced from the calculating method followed.

If instead of a negative-positive method a reversal process is used, a slightly different line of reasoning must be followed. In reversal processes a negative image is formed first which by chemical treatment and by re-exposure is reversed into a complementary positive image. That is to say, if said provisional negative image was screened, the positive image would have a number of screen dots complementary to the number of dots in the negative. Consequently, the contact screen used with the provisional negative is to be adapted to produce these complementary numbers of dots.

As regards the shape of the screen areas, it should be noted that it is possible to use all geometrical shapes which can be arranged in adjoining relationship without any interspaces being left, examples of such shapes being triangles, squares and hexagons. The latter shape is to be preferred, because owing to the alternating arrangement of the faces, the chance that lines will be seen in the screen pattern is smaller than if squares are used, while moreover the hexagon most closely approaches a circle. Such a pattern is shown in FIG. 3, the faces having not yet been provided with the required grayings. The formation of groups may be effected in different manners. A hexagonal circumference of the groups is most favorable owing to the symmetry and the optimum filling of a surface having a minimum area.

Though generally speaking the areas adjoin each other, it may sometimes be desirable to provide a division between the faces. This may be effected by means of an opaque edge between the faces.

The size of the screen areas depends on the demands

which are made on the reproduction and the lower limit of said size is determined by the surface properties of the paper to be printed. It is possible to achieve a diameter of 0.05 mm. and even less.

- 5 The calculation described above holds good for those cases where the differences in density remain unchanged during the steps of the treatment prior to the screening operation and where it is not necessary to change the number of dots in certain or in all of the density zones. 10 It will be clear that such changes can be accommodated in the given calculating scheme without difficulty, and that therefore the contact screen can easily be adapted to special treatments and materials. It is also clear that what holds good for a black and white reproduction 15 admits of being simply transferred to multi-color printing methods.

FIG. 4 is will be seen that there are two vertical columns of figures, the left column containing 7 figures and the right column 6. Furthermore there is a subdivision 20 into horizontal rows which from the top downwards are designated by the letters A-G inclusive. Consequently, the figure in the bottom right hand corner will be designated by GII etc.

- FIG. 4 is a greatly enlarged portion of a contact screen. 25 Adjacent portions of the contact screen will generally be built up in the same manner, i.e. according to the same pattern, but this is in principle not necessary. All areas of the sub-group of dark areas contained in the group of areas in FIG. A1, thirteen in this example, 30 have the same photographic density. The same applies to the darkened areas forming the sub-groups of areas shown within a group of areas the same size as the group of areas in FIG. A1 in the right column, i.e. sub-group B2 (containing twelve areas) to sub-group G2, inclusive. 35 Whereas the photographic density of the areas forming a sub-group is the same for all areas, of the sub-group, the photographic density of the overall group of areas increases stepwise from A1 to G2. In each of the FIGS. A1, B2 to G2, the areas of the sub-group are uniformly 40 distributed over the space occupied by the overall group of areas. This distribution is such, however, that as each of the various sub-groups is superposed upon the preceding sub-groups, the darkened and undarkened areas form a regular, and preferably homogenous, pattern. 45 Thus, for example, group A1 has a regular pattern as does group B2. When these two groups superposed one upon the other, they form the FIG. B1, which again has a regular and homogenous pattern, i.e. a pattern which has no predominant orientation. If the regular pattern 50 C2 is superposed on the pattern of FIG. B1, the regular and homogenous pattern C1 is formed. It should be noted that if the blackened areas are going to adjoin each other, which in the example shown occurs for the first time in FIG. E1, the white areas become separated, 55 again in a regular and homogenous pattern.

It should be borne in mind that the embodiment shown in this figure is merely an example. As shown, FIG. A1 has thirteen areas forming the sub-group. It would also be possible, however, to begin with a sub-group of five 60 areas, namely, one in each corner and one in the center. It will be evident that this would also necessitate a change in the pattern of the succeeding sub-groups having different densities.

One of the advantages of the method and the preferred embodiment of the contact screen according to the invention is that in the case of multi-color printing it is not necessary to change the screening direction, for the chance of a visible "moiré"-effect is much less than with the conventional screen pattern, the pattern according to the present invention containing many more dots.

It is also an advantage that the contact screen can be adapted in a simple manner to the materials used or to produce particular effects.

In the above example the positive will acquire the same photographic density as the negative; however it

will be clear that the distribution of dots may be so effected that the photographic density of the screened element, i.e. the positive, is greater or less than that of the starting material, i.e. the negative.

Although in the foregoing the basic idea of the invention, namely the use of screen dots of an equal area but varying in number, has been described with reference to a photographic method, said basic idea is explicitly not limited to photographic methods. The invention can also be applied to electronic devices which employ light spot scanning and which directly provide the screened printing means. Hitherto said devices have always used a variable dot size, but they can be adapted to operate with a variable number of dots.

The contact screens according to the invention may be made of any suitable transparent material e.g. glass, cellulose tri-acetate, and the like. As a rule it is preferred to use a contact screen the flexibility of which is opposite to that of the photographic printing material, i.e. in the case of photographic plates, a film screen, and in the case of films, a plate screen, so as to ensure a good contact and therefore an absence of interference figures. Because of the fact that in the graphic art vacuum cassettes are conventionally used, this is not an objection.

Finally the contact screens according to the invention can be made in a relatively simple manner by first drawing or printing a master screen on a greatly enlarged scale and blackening the areas into which said screen is to be subdivided according to the required pattern. Subsequently said screen is photographically reduced. The degree of blackening of the areas of the master screen is to be adapted to the density curve of the photographic material which, if said curve is accurately known and if the reflection and transmission factors of the blackening agents used in the master screen have been accurately measured, does not give rise to special difficulties. If the color-sensitivity of the photographic material used is accurately known, it is also possible to provide the areas of the master screen with such different colors that the desired blackening of the photographic material is obtained.

I claim:

1. A contact screen for forming a printing means for printing a picture, said screen having identical groups of small light transmitting areas, each group being made up of congruent areas, said light transmitting areas adjoining one another and the areas on the edges of the groups in parts of the screen other than the edges thereof adjoining areas of adjacent groups, each group of areas having sub-groups of areas with the photographic density of each area in a subgroup being identical to the photographic density of the other areas in the subgroup, the densities of the areas in the respective subgroups being different from the density of the areas in each of the subgroups within said group of areas and there being a subgroup corresponding to each photographic density in a series of photographic

densities, the areas of each subgroup being distributed over the total area of the corresponding group in a regular homogeneous optical pattern and the areas of each subgroup within a group together with the areas of the other subgroups within the group having a lower photographic density forming a regular homogeneous optical pattern.

5 2. A contact screen as claimed in claim 1 in which the arrangement of the areas in the groups is mutually different.

10 3. A contact screen as claimed in claim 1 in which the densities of the different subgroups of areas within a group are in an arithmetical series, and in which the logarithm of the relative number of areas in a subgroup is at least a substantially linear function of said density.

15 4. A contact screen as claimed in claim 1 in which said light transmitting areas have the shape of a regular hexagon.

20 5. A printing member for making a picture of an object to be reproduced in the form of at least one series of dots, all dots of a series having the same color and the same degree of transmission or reflection and the total area of the dots of the series in the respective portions of the image of the object being functions of the relative brightness of the corresponding respective portions of the object, the said printing member being made by exposing a base having a photosensitive layer thereon to the picture to be reproduced through a contact screen, said screen having identical groups of small light transmitting areas, each group being made up of congruent areas, said light transmitting areas adjoining one another and the areas on the edges of the groups in parts of the screen other than the edges thereof adjoining areas adjacent groups, each group of areas having sub-groups of areas with the photographic density of each area in a sub-group being identical to the photographic density of the other areas in the sub-group, the densities of the areas in the respective sub-groups being different from the density of the areas in each of the other sub-groups within said group of areas, and there being a sub-group corresponding to each photographic density in a series of photographic densities, the areas of each sub-group being distributed over the total area of the corresponding groups in a regular homogeneous optical pattern and the areas of each sub-group within a group together with the areas of the other sub-groups within the group having a lower photographic density forming a regular homogeneous optical pattern, and chemically treating the base to make a printing member thereof.
